The ornamental design for a LED-lamp, as shown and described.

DESCRIPTION

FIG. 1 is a perspective view of a LED-lamp showing our new design,

FIG. 2 is a front view of the LED-lamp according to FIG. 1; FIG. 3 is a right side view of the LED-lamp according to FIG. 1;

FIG. 4 is a back view of the LED-lamp according to FIG. 1; FIG. 5 is a left side view of the LED-lamp according to FIG. 1;

FIG. 6 is a top view of the LED-lamp according to FIG. 1; and, FIG. 7 is a bottom view of the LED-lamp according to FIG. 1.
